UNITED STATES PATENT OFFICE.

THOMAS D. SEGEBERG, OF SOMERVILLE, MASSACHUSETTS.

TOY.

Application filed June 11, 1924. Serial No. 719,399.

To all whom it may concern:

Be it known that I, THOMAS D. SEGEBERG, a citizen of the United States, residing at Somerville, in the county of Middlesex and 5 State of Massachusetts, have invented certain new and useful Improvements in Toys, of which the following is a specification.

This invention relates to an improved toy and has general reference to a floating 10 balloon.

The present invention relates to a combination of miniature parts, which are adapted to simulate, as far as possible, an actual balloon carrying a parachute, from 15 which a human being is suspended, and supported in flight during the descension of the parachute.

More specifically speaking, I propose to provide a gas filled balloon, a parachute 20 which is weighted by an imitation figure, and novel means which is arranged between the balloon and the parachute, for automatically releasing the latter at a predetermined time.

One feature of the invention is derived 25 from the use of a common toy balloon of the gas filled type, which permits ready attachment of the improved automatic expansion device, parachute, and parachute re- 30 leasing means thereto.

Another feature and a resultant advantage is produced by so constructing the device, as to permit the escape of all gas that is left in the main balloon, immediately 35 after the parachute has been released for descension, whereby the balloon and means which it carries, will fall to permit it to be reused.

Furthermore, I provide a novel device of 40 this class, which is comparatively simple in construction, exceedingly light in weight to insure effective floating, and inexpensive to both the manufacturer and user.

Other features and advantages of the in- 45 vention will become apparent from the following description and drawings.

In the accompanying drawing, forming a part of this application, and in which like numerals are employed to designate like 50 parts throughout the same, the figure shows, partly in elevation, and partly in section, a toy constructed in accordance with the present invention.

Referring now to the drawings in detail, 55 it will be observed that the toy balloon is designated by the reference character 1, and

as usual this balloon is provided with a neck 2 by means of which it is filled with an expansion gas. The miniature parachute is designated by the reference character 2^a, 60 and this is normally in a contracted condition. The supporting strings of the parachute are permanently connected with a figure 3, which in the present instance simulates a living aviator. For a purpose to be 65 hereinafter described, the parachute is provided at its top with an attaching eye 4. In accordance with the present invention, I use an elongated aluminum tube 5, which is pointed at its opposite ends. At its lower 70 end the tube is closed, while at its upper end it is provided with a restricted intake port 6. Also, at a point intermediate its ends it is provided with a discharge port 7. A hooked latch 8 is pivoted to the lower 75 end of a tube, in any suitable fashion, and in practice, the hook of the latch is connected to the eye 4 on the parachute, in the manner shown in the drawing. Furthermore, if desired, the tube may be provided adjacent 80 its upper end with a circumferential rib or bead 9, for disposition in the neck 2 of the balloon to assist in maintaining the parts in assembled relation.

The so-called expansion device and latch 85 releasing device is in the form of a double-chamber rubber balloon 10, which has its upper end fixed to the tube 5, and has its lower end slidably connected to the tube. In carrying out the latter result, I attach 90 the portion 11 to the part 10, so as to insure rigidity of construction, free sliding, and a fluid tight joint. It is to be observed that the expansion chamber or balloon 10 is attached to the tube 5 at a point above the 95 fluid escape port 7, so that the escaping fluid will enter the chambers to distend the device as seen in dotted lines.

In practice, the toy is used in the following manner. The toy balloon 1 is preferably 100 pre-filled with gas and the neck 2 is tied with a string in the usual way, to prevent escape of the gas. This part is normally expanded when the toy is bought. The string used to close the neck 2 is preferably tied 105 by a slip knot or its equivalent, so that it may be readily united. Then, too, the string is tied to the neck at a point quite close to the body of the balloon, so as to leave a projecting portion to permit insertion of the 110 upper pointed end of the tube 5, before the string is disconnected. In this manner, es-

cape of gas from the balloon is obviated.

By simultaneously untying the string and inserting the tube, the parts take the position illustrated in the drawing. Now, while the balloon ascends, the gas from the interior thereof slowly escapes through the intake port 6 and passes out through the port 7 into the superposed chambers of the expansion device 10. The latter is comparatively light in weight and is readily expanded by the incoming gas. When the element 10 is fully distended, the washer 11 on the bottom thereof comes into contact with the upper free end of the latch 8, thus swinging the latter upon its pivot and disconnecting it from the eye on the parachute. Thus, while the device is suspended in the air, the parachute is released, and the weighted body 3 causes the parachute to open and permits slow descent of the parachute and figure. In this way, the device simulates a full sized balloon releasing a parachute and man for a down flight. It is to be observed that at about the same time the latch is released, the washer 11 moves down over the lower pointed end of the tube 5, and hence, it is only a short time until the entire gas content of the main balloon 1 is released, thereby permitting the latter to come down and be used over again.

Undoubtedly the foregoing description, when taken in connection with the accompanying drawing, will suffice to enable the reader to obtain a thorough comprehension of the invention. For this reason, it is thought that a more lengthy description is unnecessary.

While I have shown and described the specific embodiment of the invention, I wish it to be understood that changes may be resorted to, such as fall within the scope of the adjoined claims.

I claim:

1. A toy comprising a balloon, a weighted parachute, and means interposed between the two for automatically releasing the parachute at a predetermined time.

2. A toy of the class described comprising a balloon, a release device carried thereby, a parachute connected with said device, and a balloon controlled expansion means active on said device for automatically releasing the parachute at a predetermined time, during the flight of the toy.

3. A toy of the class described comprising a balloon, a tube inserted into the neck of the latter and having an air intake and a discharge port in communication with the interior of the balloon, a latch on said tube, a parachute detachably connected with said latch, and an expansion device acted on by the escaping fluid from the balloon for automatically operating said latch at a predetermined time to release the parachute.

4. A toy of the class described comprising a balloon inflated with gas, said balloon having a contractible filler neck, a gas conveying tube inserted into the neck and having a gas intake in its inner end provided with a gas discharge port intermediate its end, a flexible expansion device surrounding and fixed at the upper end to said tube at a point above said discharge port, the lower end of said device having a slidable connection with the tube at a point below said port, so that it will be slowly distended by the escaping gas, a hooked latch pivotally connected to the lower end of the tube, a parachute having an attaching eye to which the hook of said latch is normally connected, and a weighted toy figure carried by the supporting strings of the parachute.

5. In a toy of the class described, a tube tapered at its opposite ends, one of said ends being provided with an opening, said tube being provided intermediate its ends with a second opening, a hooked latch pivoted to the lower end of the tube, and a chambered expansion element surrounding the tube and having its ends connected with the latter at points above and below the second named opening.

In testimony whereof I affix my signature.

THOMAS D. SEGEBERG.
